ILLUMINATABLE VANITY CASE AND LIKE CONTAINER

John Giacomo Pucci, Westerly, R. I.

Application March 27, 1940, Serial No. 326,245

2 Claims. (Cl. 240—6.45)

My invention relates to improvements in containers having a light therein, particularly in the type of a container adapted to be carried in a small bag, hand, or pocket, such as a vanity case, cigarette case, etc.

An object of my invention is to provide a device which is a container for small objects, such as cosmetics, cigarettes, etc., and which at the same time may be used as a flashlight.

A further object of my invention is to provide a container having a light so mounted therein, preferably countersunk in the cover thereof so as to concentrate a beam of light on a desired area by relative movement of the cover in which the light is mounted relative to the base of the container, it being apparent that if the cover be also provided with a mirror a person adjacent the device can look in the mirror and see a reflection of an object on which the beam of light is concentrated. This is particularly desirable in the case of the application of cosmetics, such as lipstick when the user of the vanity case can relatively pivot the cover to concentrate the beam of light on her lips and then look in the mirror to insure the correct application of the lipstick in the dark.

A further object of my invention is to provide suitable means to shut off the light when it is not needed in the dark or in the light.

A further feature of my invention is to provide a device which may be so used and which may, if desired, be independently used as a flashlight.

While there have been various attempts to mount lights in vanity cases in the prior art, so far as the applicant is aware these lights have been mounted to project either vertically outwards or longitudinally upwards of the vanity case. The applicant has discovered that if such a light be mounted to extend transversely of a light holding compartment, that such a manner of mounting permits the cover of the container to be made much thinner than hitherto, so that the container of itself may have a thickness approaching that of a standard vanity case or a cigarette case.

A further object of my invention is to provide means automatically operated by the opening and closing of the light holding compartment cover to respectively light and shut off the light.

A further object of my invention is to provide a construction wherein the cover of the light holding compartment may, if desired, be supplementally pivoted to shut off any light from the user's eyes.

A further feature of my invention relates to the specific structure of the various parts thereof, which are readily and simply fabricated and mostly comprise standard electrical and other parts now on the market.

5 These and such other objects of my invention as may hereinafter appear will be best understood from a description of embodiments thereof such as illustrated by the accompanying drawings applied to a vanity case.

10 In the drawing, Fig. 1 is a longitudinal vertical sectional view through a closed vanity case constructed in accordance with my invention.

15 Fig. 2 is a transverse sectional view thereof taken along the line 2—2 of Fig. 1.

Fig. 3 is a longitudinal vertical sectional view similar to Fig. 1 with the cover pivoted open relative to the base and with the light holding compartment cover pivoted to open position.

20 Fig. 4 is an end elevation looking towards the cover in open position as shown in Fig. 3.

25 Fig. 5 is a fragmentary longitudinal vertical sectional view similar to Fig. 1 showing an alternative embodiment of my invention wherein the light holding compartment projects beyond the end of the vanity case so as to have its cover open independently of the relative closed and open positions of the vanity case for the independent use of the device as a flashlight.

30 In the drawing, wherein like characters of reference indicate like parts throughout, 10 generally indicates a vanity case constructed in accordance with my invention, although it is apparent that certain features of my invention are applicable to other types of containers preferably those of a size to be normally carried in the bag, pocket or hand of the user such as a cigarette case, key case, etc. Said container 10 comprises the usual base 12 and the usual cover 14 pivotally mounted on said base. Said cover is provided as usual, with the end walls 16 and the side walls 18. I provide a partition 20 extending transversely between the side walls 18 adjacent the free end of said cover and at a closely spaced 35 distance from the upper end thereof when in open position, forming an upper light holding compartment 22. It is obvious that an additional compartment 24 for holding a storage battery is thus provided below said partition 20 which 40 may if desired, also be used for other purposes. If desired, this lower compartment may be subdivided by a partition 25 extending longitudinally from substantially the center of said partition 20 to the lower end wall 16 thereof forming a 45

50 battery holding compartment 24 in one portion

thereof, in the embodiment shown, to the left of said partition 25 over which the light holding socket is preferably mounted and another compartment portion 27 which may be used for holding additional objects, such as a lipstick, money, cigarettes, etc. In the embodiment shown the base 12 is adapted to hold cosmetics and is provided with a suitable cosmetic dispensing surface 15 of any suitable nature known in the art. A suitable storage battery 26 is contained in the battery holding compartment 24, preferably of the standard type having the split contact arms 28 and 29 projecting upwardly therefrom, the battery holding portion of the lower compartment 24 in said cover 14 being of a size to compactly hold a suitable storage battery without rattling.

An electric light 30 is suitably mounted in said light holding compartment 22, preferably in the manner to be explained, to extend transversely of said upper light holding compartment 22. As stated hitherto, lights have been mounted to extend longitudinally of a cover of a vanity case or to project vertically outwardly from said cover, but so far as the applicant is aware none have been mounted transversely of a light holding compartment in the cover. This is possibly the reason why lights have not been commonly installed in vanity cases, as such a mounting inherently makes the walls of the cover so thick as to provide an unsightly container. Employing my invention, however, it is possible to suitably countersink the light 30 within the compartment 22 in the cover and still maintain the walls of the container of such an attractive thinness as to provide an article having a marketable appeal.

While any suitable type of means 32 may be provided to suitably mount the electric light 30 preferably transversely within said compartment 22, I preferably provide a split electric light base holding socket or clip 32 mounted on said transverse partition 20 within said light holding compartment with the split end 34 thereof outermost so that the base 36 of said electric light 30 may be removably mounted thereon and I also provide a suitable type of switch means 38 to connect said battery 26 to said light 30 preferably comprising a spring make and break switch.

In the embodiment shown, I preferably provide a cover 38 for said light holding compartment 22 pivotally mounted on the upper extremity of the top wall 16 of said cover 14 to be movable from an open position permitting a concentration of light to be reflected outwardly from said compartment 22 to a closed position shutting off said light. It is obvious that suitable latch means (not shown) are provided to latch the cover 14 to the base 12 and to latch the compartment cover 38 in a closed position over said light holding compartment 22, the mirror base 14 to partition 20 and the cosmetic dispensing cover to base 12 and also if desired, spring means (not shown) to swing the respective covers open when the respective latches are released, as are commonly used in vanity cases. A cover may also be provided over battery 26, if desired. In the embodiment shown in Figs. 1-4 the cover 14 is made the same length as the base 12 so that the compartment cover 38 can only be opened when the cover 14 is relatively moved away from said base. In the embodiment shown in Fig. 5, I have provided a construction wherein the cover 14' is longer than its relative base 12 so that the light holding compartment 22 projects longi-

tudinally beyond the end of the base 12 and it is apparent that with this specific construction that the light holding compartment cover 38' may be independently opened to have my improved device function as a flashlight, even if the main container thereof be closed.

In the embodiments shown, the light base holding socket 32 is preferably constructed out of resilient flat stock having the base 48 thereof overlying said transverse partition 20 and an integral preferably U-shaped split socket portion 42 mounted on said base within said compartment 22 with the split open U-end 34 thereof outermost. The base 36 of the electric light 30 is then detachably secured within said split socket 42 so that the light 30 may extend transversely of said compartment 22 when the base 36 thereof is detachably secured within said split socket 42. Suitable means are provided on the interior of the socket 42 to threadedly secure the base 36 therein such as the projection 43 projecting radially inwardly thereof shown to mesh with the usual external threads 45 on the base.

In the preferred embodiment shown, the switch means 38 to connect the battery 26 to the light 30 preferably comprises a spring make and break switch connecting said battery and light, preferably so constructed as to function to turn off the light on closing of the compartment cover 38. In the preferred embodiment shown, said spring make and break switch 38 is preferably constructed as follows: A contact means such as the screws, or rivets 44 extend through said partition 20 to mount said socket base 48 on said partition 20 and to contact a battery contact such as the switch arm 28, the socket base 48 being suitably insulated from the partition by the insulating strips 47. The spring make and break switch 38 connecting said battery and light also includes a stationary arm 48, which is suitably insulatedly mounted on the portion of said socket 42 below said split 34. Said stationary arm 48 is then bent outwardly as at 50 to contact the contact 52 on the light base 36 and then extends transversely near the open end of said light holding compartment 22. Said make and break switch also includes a spring arm 56 having a base 58 overlying said partition 20 and having a bent portion 60 normally urged by the resiliency of said arm to have a portion 62 thereof project beyond the open end of said light holding compartment 22 and terminating in an end 64 to contact the contact end 54 of said stationary contact arm 48 to light the light 30. It is thus obvious that this type of switch is controlled by the opening and closing of the light holding compartment cover 38 when said cover is opened, said portion 62 normally projecting beyond the open end of said compartment 22 and the contact end 64 thereof contacting the stationary contact 54 to light the light. It is apparent, however, that when said cover is closed, it abuts said portion 62 normally projecting beyond the open end of said compartment 22 to depress it and to free the contact 64 thereof from the stationary contact 54 to positively extinguish the light 30 when the cover 38 or 38' is closed. It is apparent, however, that any suitable type of make and break contact switch may be employed, preferably one controlled by the opening and closing of the light holding compartment cover 38. To complete the circuit from said spring arm 56 to the battery 26, a contact member or means such as the screws or rivets 66 extend through said partition 20 to mount the base 58 of said spring arm on said partition 20 and to con-

tact the other battery spring arm 29. I also provide the mirror 70 normally overlying the lower portion of said cover 14 or 14' below said partition 20, namely, the battery holding compartment 24 which is preferably independently movable from over said compartment for replacement of a battery if desired. In the embodiment shown, said mirror 70 is preferably pivotally mounted, if desired, as shown, on the same pivot pin 72 as that on which the cover 14 or 14' is pivotally mounted on said base 12. For this purpose the base 14 on which the mirror 70 is mounted has a suitable ear 76 for the independent pivotal mounting of said mirror 70 on said pin 72.

As illustrated in Fig. 3, the cover 14 may be pivoted relative to said base 12 to such an open position in such a manner as to converge the light from said light 30 within said compartment 22 on a desired area, such as a portion of the person to which the cosmetic is to be applied, as the lips of said person if it desires to apply lipstick thereto. It is then apparent that the lighted lips may be readily observed by said user in the mirror 70 so that said person may apply the lipstick thereto as efficiently in the dark as it could in the daylight and so that there will be no glare in the user's eyes. If desired, the light holding compartment cover 38 or 38' may be relatively pivoted to additionally shut off the beam from the eyes. It is apparent that this provides a very convenient structure, for the entire device can be held in one hand and the cosmetic readily applied by the applicator from said base 12 held in one hand while the other hand is holding the cover 14 or 14' open in the desired relative manner to concentrate the light on the desired area to which the cosmetic is to be applied.

It is also apparent that if desired the device may be independently used as a flashlight on opening of the compartment cover 38, particularly a device constructed as in the embodiment shown in Fig. 5, wherein the compartment cover 38' thereof may be opened independently of the container cover 14'. It is thus apparent that by mounting the light transversely of the container I am enabled to provide a container of such small thickness as to make its use applicable to thin articles of personal use, such as vanity cases and cigarette cases, etc.

It is also apparent that I have provided in a container a novel type of means to concentrate the light from a light source countersunk therein on a desired area so that the desired area may be viewed in the dark in the mirror and with the other advantages hitherto described above.

It is understood that my invention is not limited to the specific embodiments shown and that various deviations may be made therefrom without departing from the spirit and scope of the appended claims.

What I claim is:

1. In a vanity case, a cosmetic dispensing base, a cover pivotally mounted on said base having end and side walls, having a partition extending transversely between the side walls thereof at a closely spaced distance from the upper end thereof when in closed position forming an upper light holding compartment, and a lower battery holding compartment, a battery having contacts at the upper end thereof contained in said battery holding compartment, a split electric light base

holding socket having the base thereof overlying said transverse partition and a split socket mounted on said base within said compartment with the split end uppermost, an electric light extending transversely of said compartment with the base thereof detachably secured within said split socket, a contact member extending through said partition to mount said socket base on said partition and contact a battery contact, a spring make and break switch operatively connecting said battery and light comprising a stationary contact arm insulatedly mounted on said socket, contacting the light base contact and terminating in a contact end extending transversely near the top of said light holding compartment, a spring contact arm having a base overlying said partition, a bent portion normally urged by the resiliency of said arm to have the top of said bent portion project beyond the top of said light holding compartment and a transversely extending end contacting said stationary contact arm to light the light, a cover for said light holding compartment pivotally mounted on said cover movable to a compartment closing position abutting said bent portion of the contact arm to break the contacts on said make and break switch to extinguish said light when said cover is closed, a contact member extending through said partition to mount the base of said spring contact arm on said transverse partition and contact the other battery contact and a mirror normally overlying the lower portion of said cover, whereby said cover may be relatively pivoted to a position to bring the light opposite the portion of the person to which the cosmetic is to be applied and said portion may be readily observable in the mirror.

2. In a vanity case, a cosmetic dispensing base, a cover pivotally mounted on said base having end and side walls, having a partition extending transversely between the side walls thereof at a closely spaced distance from the upper end thereof when in closed position forming an upper light holding compartment and a lower battery holding compartment, a battery having contacts at the upper end thereof contained in said battery holding compartment, a split electric light base holding socket comprising resilient flat stock having the base thereof mounted on said transverse partition and a substantially U-shaped split socket mounted on said base within said compartment with the split open U-end uppermost, an electric light extending transversely of said compartment with the base thereof detachably secured within said split socket, a spring make and break switch connecting said battery and light having a bent portion normally urged by the resiliency thereof to have the end of said bent portion project beyond the top of said light holding compartment to light the light, a cover for said light holding compartment pivotally mounted on said cover movable to a compartment closing position abutting said projecting spring portion to extinguish said light when said cover is closed and a mirror normally overlying the lower portion of said cover, whereby said cover may be relatively pivoted to a position to bring the light opposite the portion of the person to which the cosmetic is to be applied and said portion may be readily observable in the mirror.

JOHN GIACOMO PUCCI.
